UNITED STATES PATENT OFFICE.

FRANK POWYSZENSKI, OF CHICAGO, ILLINOIS.

REMOVABLE HEEL.

1,029,220.

Specification of Letters Patent. Patented June 11, 1912.

Application filed January 29, 1912. Serial No. 674,064.

To all whom it may concern:

Be it known that I, FRANK POWYSZENSKI, a subject of the Czar of Russia, and a resident of Chicago, in the county of Cook, 5 State of Illinois, have invented certain new and useful Improvements in Removable Heels, of which the following is a specification.

This invention relates to removable heels 10 for shoes and like foot wear, and more especially to that type of removable heels in which the heel members are attached together by a dovetail connection. And the present improvement has for its object to 15 provide a simple and efficient structural formation and combination of parts whereby a very strong and substantial connection of the heel member is effected in a readily detachable manner, all as will hereinafter more 20 fully appear.

In the accompanying drawings:—Figure 1, is a longitudinal section on line $x-x$, Fig. 2, of a heel embodying the present invention. Fig. 2, is an elevation of the forward end of the heel. Fig. 3, is an inverted plan view on line $x'-x'$, Fig. 1, of the fixed heel member. Fig. 4, is a plan view on line $x'-x'$, Fig. 1, of the removable heel member. Fig. 5, is a transverse section on line 30 x^2-x^2 , Fig. 1. Fig. 6, is a detail perspective view of the combined reinforcing member and nut of the removable heel member.

Similar reference numerals indicate like parts in the several views.

Referring to the drawings, 1 represents the upper member of the shoe heel forming a fixed part of the shoe, and which in the present construction is formed with a U shape central projection 2 on its under side, 40 the marginal walls of which are undercut as shown, to constitute a portion of the dovetail connection hereinafter described. The said projection 2 is also formed with a central longitudinal bore 3, for the passage of 45 the hereinafter described attaching bolt.

4 is the removable heel member formed with a central U shape recess 5, on its upper

face, the marginal walls of which are undercut to correspond with and fit the undercut walls of the projection 2 of the fixed heel member 1 aforesaid, and constitute the dovetail connection by which the heel members are connected together in a firm and substantial manner.

6 is the longitudinal screw or bolt above 55 referred to, arranged in the longitudinal bore 3 of the projection 2 aforesaid, and having a head 7 that has bearing against the forward end of said projection 2, as shown.

8 is a screw-threaded lug located at the 60 rear end of the recess 5 aforesaid, and carried on the rear end of the hereinafter described reinforcing member. Said lug is adapted for engagement with the screw-threaded end of the longitudinal bolt 6, 65 aforesaid.

9 is the metal reinforcing member above 70 referred to, and which is embedded in the material of the removable heel member 4, as shown. At its rear end the member 9 carries the centrally arranged screw-threaded lug 8, and at its forward end a pair of counterpart inclined lugs 9', the inner faces of which are preferably flush with inclined side walls of the dovetail recess 5, aforesaid, to form parts thereof.

In the preferred form of the present invention the inclined side lugs 9' are integrally connected together by a transverse web, as shown, and in like manner connected 80 to the screw-threaded lug 8, by curved webs 10, the whole forming a skeleton reinforcing member adapted to be securely embedded in the material of the removable heel, and afford strength and stability to the engagement between the hub parts.

With the present improvement the longitudinal bolt 6, not only holds the parts in proper position, but in addition is adapted to draw the same together in such position. 90

Having thus fully described my said invention what I claim as new and desire to secure by Letters Patent, is:—

A removable heel, comprising a fixed and

a removable member, one member being formed with a dovetail projection and the other with a counterpart dovetail recess, a reinforcing member embedded in the member containing the dovetail recess aforesaid, and having a vertical screw-threaded lug at its rear end and a pair of inclined lugs at its forward side ends, and a longitudinal bolt passing through the aforesaid dovetail

projection and engaging said screw-threaded lug, substantially as set forth.

Signed at Chicago, Illinois, this 26th day of January, 1912.

FRANK POWYSZENSKI.
